United States Patent Office

Des. 225,804
Patented Jan. 9, 1973

225,804

STUDENT DESK

Frank R. Torrey, 9805 Dallas Ave.,
Silver Spring, Md. 20901

Filed Feb. 19, 1971, Ser. No. 117,181

Term of patent 14 years

Int. Cl. D6—04

U.S. Cl. D6—138

FIG. 1

FIG. 2

FIG. 3

FIG. 1 is a perspective view of a student desk, showing my new design;

FIG. 2 is a rear end elevational view thereof, and
FIG. 3 is a bottom elevational view thereof.

I claim:

The ornamental design for a student desk, as shown and described.
